(57) **CLAIM**

The ornamental design for the “two piece screw cap closure,” as shown and described.

DESCRIPTION

FIG. 1 is a front perspective view of the screw cap portion of a two piece screw cap closure showing our new design. FIG. 2 is a front perspective view of the closure body portion thereof.

FIG. 3 is a side view of the assembled two piece screw cap closure with partial cross-sectional view.

FIG. 4 is a side view of the screw cap with partial cross-sectional view.

FIG. 5 is a top view of the screw cap.

FIG. 6 is a side view of the closure body with partial cross-sectional view; and,

FIG. 7 is a top view of the closure body.
